UNITED STATES PATENT OFFICE.

CHARLES W. WERTZ, OF TOLEDO, OHIO.

BUSTLE.

SPECIFICATION forming part of Letters Patent No. 400,149, dated March 26, 1889.

Application filed July 9, 1888. Serial No. 279,433. (No model.)

To all whom it may concern:

Be it known that I, CHARLES W. WERTZ, a citizen of the United States, residing at Toledo, in the county of Lucas and State of Ohio, 5 have invented certain new and useful Improvements in an Adjustable Bustle; and I do hereby declare that the following is a full, clear, and exact description of the invention, which will enable others skilled in the art to 10 which it appertains to make and use the same, reference being had to the accompanying drawings, and to the letters of reference marked thereon, which form part of this specification.

15 My invention relates to an adjustable bustle of that character wherein there are employed a series of coiled springs having their upper ends secured to the vertical or rectangular frame or form and the lower ends thereof 20 free to contract vertically when desired.

The object of the invention is to provide a frame-work beneath the coils that shall have an adjustability to vary the fullness of the bustle by raising the coils, and that when adjusted will rigidly hold the coils to the desired 25 height, thereby giving the bustle any desired fullness.

The invention consists in the parts and combination of parts hereinafter described, and 30 pointed out in the claims.

In the drawings, Figure 1 is a perspective view of the under side of the bustle, showing in full lines the frame expanded and the coils in normal position, and in dotted lines the 35 frame contracted with the line of expansion of the coils. Fig. 2 illustrates a form of covering for the vertical frame or form having means for contracting the same by a lacing.

A designates a vertical or rectangular frame 40 or form, the top and sides thereof being of wire, and the lower portion consisting of a strap, B, attached at each end to coils in the side wires, and provided with a buckle, C, by which to adjust the strap to any desired length 45 to allow for contraction or expansion of the frame connected thereto. Each side wire, D, of the vertical or rectangular frame is coiled at E, the coil ending in a spring-arm, E', as shown.

50 F designates the band to the bustle attached

to the horizontal wire of the vertical frame or form, F' being a tape of greater width attached to the horizontal wire and to the side wires, D.

G are a series of coil-springs, shown as covered with a suitable fabric and attached to 55 the rectangular frame at the point of attachment of the band and tape, the lower portion of the coils depending therefrom in the arc of a circle.

H and II' are bails having triangular top 60 and base portions, the strap B being the base of the lower triangle. Each bail is formed with a horizontal portion, I, and side bars, K, bent at acute angles to the horizontal portion and crossed at a point about centrally of their 65 lengths, the ends of each side bar being secured in the coils of the side wires of the form or rectangular frame. The side bars of bail H' are engaged by the hooked ends E'' of the spring-arms E'. Each horizontal portion I of 70 the bails is attached to the covering of the coils by loops L, the lower bail, II', being attached about centrally of the length of the coils, and the upper bail, H, at a point nearer the upper end of the coils.

75 M is a tape secured to the coils by a loop, M', and to bail II at a point where the side bars cross.

With the bustle in its normal position, as 80 shown in full lines, Fig. 1, to give the bustle more fullness by raising the coils relatively to the form, adjusting-strap B is shortened by pulling one end through buckle C and securing the same therein. This has the effect of contracting side wires, D, thereby projecting 85 bails H and II' upwardly, as shown in dotted lines, and as a consequence the coils, which may be caused to assume the degree of fullness indicated by dotted lines.

In Fig. 2 is shown a form of cover, N, for 90 the rectangular frame or form, which is attached to the upper and side portions of the rectangular frame or form, in which event the adjusting-strap and buckle are omitted, and the side wires are contracted or allowed to 95 expand by tension of a lacing, O, in cover N, the expansion or contraction of the lacing producing the same effect upon the frames and coils as has been described.

100 By means of rectangular frame or form A

and bails II II' the bustle is held firmly to any degree of fullness determined by the expansion or contraction of the bails, and the lower portion of the coils has a free vertical 5 movement to allow the same to fold out of the way of the wearer when in the act of sitting. By reason of the spring-arms bearing upon bail II' and the coils being connected with frame H through the medium of tape M, 10 the bustle at all times quickly assumes its normal position when released from having been folded in the act of sitting.

While I have shown two bails, it will be apparent that I may employ but one, or more 15 than two, without departing from the spirit of my invention.

What I claim is—

1. In a bustle, a vertical frame provided with eyes at each lower extremity and coiled 20 springs attached at their upper ends to the upper edge of said vertical frame, in combination with one or more bails connected at their lower ends with the eyes of the vertical frame and extending obliquely upward and

outward to a connection with the under side 25 of said coiled springs, and a flexible diaphragm connecting the lower ends of the vertical frame and serving to contract the same for raising the coils, substantially as described.

2. In a bustle, the combination of a vertical 30 frame having side bars formed with eyes at their lower ends, said eyes terminating in spring-arms, said arms having loops which embrace the bails, coiled springs attached to the upper portion of the vertical frame, bails connected with said coiled springs and with the eyes of the side bars, and an adjusting-strap 35 connected to the side bars of the vertical frame for contracting the same, substantially as set forth.

In testimony that I claim the foregoing as my own I hereby affix my signature in presence of two witnesses.

CHARLES W. WERTZ.
